UNITED STATES PATENT OFFICE.

ONIS MARCUS LEONARD, OF MACY, INDIANA.

BREECH FOR TORPEDO-TUBES.

1,247,417.

Specification of Letters Patent.

Patented Nov. 20, 1917.

Application filed March 3, 1917. Serial No. 152,330.

To all whom it may concern:

Be it known that I, ONIS M. LEONARD, a citizen of the United States, residing at Macy, in the county of Miami and State of Indiana, have invented certain new and useful Improvements in Breeches for Torpedo-Tubes; and I do hereby declare the following to be a full, clear, and exact description of the invention, such as will enable others skilled in the art to which it appertains to make and use the same.

The invention relates to a torpedo tube breech.

The object of the present invention is to improve the construction of torpedo tubes, more especially the breech construction, and the mechanism for firing the torpedo from the tube, and to provide a simple, practical and efficient construction which will be strong durable and inexpensive and which will be adapted to relieve submarines of the weight of many tons of mechanism ordinarily employed in connection with the firing or discharge of torpedoes from torpedo tubes.

A further object of the invention is to lessen the cost of firing torpedoes from torpedo tubes and to increase the effectiveness of the mechanism employed for discharging the torpedoes from tubes.

With these and other objects in view, the invention consists in the construction and novel combination of parts hereinafter fully described, illustrated in the accompanying drawings and pointed out in the claims hereto appended; it being understood that various changes in the form, proportion, size and minor details of construction, within the scope of the claims, may be resorted to without departing from the spirit or sacrificing any of the advantages of the invention.

In the drawings:

Figure 1 is a longitudinal sectional view of a torpedo tube provided with a breech constructed in accordance with this invention.

Fig. 2 is an enlarged longitudinal sectional view through the breech of the torpedo tube.

Fig. 3 is a transverse sectional view on the line 3—3 of Fig. 1.

Fig. 4 is a similar view on the line 4—4 of Fig. 1.

Fig. 5 is an end elevation of the breech.

Fig. 6 is a detail sectional view on the line 6—6 of Fig. 5.

Like numerals of reference designate corresponding parts in the several figures of the drawings.

In the accompanying drawings in which is illustrated the preferred embodiment of the invention 1 designates a torpedo tube designed for use in a submarine 2^a or other vessel and the mechanism herein described may be employed for discharging torpedoes and projecting the same into the water by any suitable means. The torpedo tube 1 is provided at the rear end with a breech 2 removably mounted on the torpedo tube by any suitable means. In the accompanying drawings a band 3 is shown having a threaded engagement with the breech and with the rear end of the torpedo tube, but any other suitable means may of course be employed.

The torpedo tube receives a torpedo 4 which fits the interior of the torpedo tube in the usual manner and forms a rear chamber 5 in the rear portion of the torpedo tube for the reception of the pressure employed for expelling the torpedo from the tube,

and in order to eliminate the pressure pumps, tanks and other heavy machinery ordinarily employed on submarines and the like for this purpose, the breech is equipped for expelling the torpedo from the tube,

and in order to eliminate the pressure pumps, tanks and other heavy machinery ordinarily employed on submarines and the like for this purpose, the breech is equipped with an evaporating cup 6 designed to be supplied with liquid air, ammonia or other suitable gas forming liquid, which is fed to the evaporating cup in the desired quantity by means of a supply pipe 7. The supply pipe 7 is extended through the breech and is provided with an arm or branch 8 which extends upwardly to and is connected with the bottom of the evaporating cup at an inlet aperture 9 thereof. The liquid air, ammonia or other gas forming liquid may be stored in a suitable vessel or receptacle and will weigh comparatively little with respect to the heavy pumps and tanks ordinarily employed for the expulsion of torpedoes from torpedo tubes on submarines. The liquid air, ammonia or other liquid of like character is evaporated and converted into

gas of the desired pressure by means of electrically heated members 10 extending into the evaporating cup and consisting of copper plates in the accompanying drawings, but any other form of heating element may of course be employed and the cup is insulated electrically at 11. The electrically

heated plates, which may be varied in size and number to secure the desired amount of heat, are connected with insulated contacts or binding posts 12 extending through the 5 breech and adapted to be connected with suitable electrical conductors for supplying the current for heating the copper plates or other heating elements. The insulation may be of any desired character and only a 10 comparatively small cup will be required for producing a pressure of the desired degree. By varying the amount of the liquid air, ammonia or other material and the amount of heat to which the same is subjected, the 15 required pressure may be produced in the desired time, which, owing to the heating means, will be practically instantaneous.

The cup is arranged within a chamber 13 formed by a transverse disk or plate 14 and 20 the breech and the said disk or plate is of the same diameter as the interior of the torpedo tube and is connected with the breech by means of an annular series of bolts 15, a 25 spacing sleeve or member 16 being interposed between the disk and the breech to prevent the cup from being crushed. The spacing member or sleeve, which is arranged exteriorly of the annular series of bolts 15, is preferably flared at its inner and outer 30 ends, as shown, and it constitutes the side walls of the cup-receiving chamber. By this construction the cup and the heating elements are housed within the breech mechanism. The heating elements are connected 35 with each other and with the binding posts or terminals of the conductors which convey the current to the heating means.

The torpedo is provided at the rudder with a hook or engaging member 17, which 40 is engaged by a correspondingly shaped arm or engaging portion 18 of a releasing shaft 19 extending through the disk and the breech and provided at its outer end with an operating device 20, which is preferably 45 in the form of a crank handle and which is adapted to be operated to swing the hook or engaging arm of the shaft out of engagement with the hook or engaging member of the torpedo. The torpedo holding and releasing device connects the torpedo with the 50 breech so that the internal pressure which passes through apertures 22 of the plate of the breech acts against both the breech and the torpedo until the torpedo is released. 55 and thereby assists in holding the breech in place, the breech being subjected to the maximum pressure only when the torpedo is released. The breech is provided with a centrally arranged stuffing box 23 through 60 which the holding and releasing shaft extends, but any other suitable means may of course be employed for mounting the said shaft which is also provided with an abutment 24 for engaging the disk or plate. 65 The abutment may be in the form of a nut,

or any other suitable means, and when the shaft is rotated the hook-shaped arm or portion 18 is moved into or out of engagement with the arm or hook at the rudder of the torpedo. Various other means may be employed for detachably connecting the torpedo with the breech and for releasing the torpedo when the desired pressure has been developed in the pressure chamber at the rear end of the torpedo tube. 75

It will be seen that practically the required pressure for discharging a torpedo may be almost instantly developed in the pressure chamber at the rear end of the torpedo tube and that very little mechanism is so required to supply the evaporating cup with the gas forming liquid and for creating the necessary heat to develop the gas pressure and that the mechanism will reduce the weight of torpedo expelling or discharging 85 mechanism at least eighty-five per cent. and that the cost of firing torpedoes will be materially reduced.

What is claimed is:

1. A device of the class described including a torpedo tube provided with a breech and having an evaporating receptacle adapted to be supplied with a gas forming liquid, and means for supplying heat to the receptacle for converting the liquid into gas of the 95 desired pressure.

2. A device of the class described including a torpedo tube provided with a breech and having an evaporating receptacle adapted to be supplied with a gas forming liquid, 100 and electrically heated elements for supplying heat to the receptacle for converting the liquid into gas of the desired pressure.

3. A device of the class described including a torpedo tube, a receptacle located within the tube and adapted to contain a gas forming liquid, means for supplying heat to the receptacle for converting the liquid into gas of the desired pressure, and means for holding a torpedo in the tube and for releasing 105 the torpedo after the pressure has developed.

4. A device of the class described including a torpedo tube having a breech, means for supplying a gas producing liquid to the 115 torpedo tube, means for heating the liquid for converting the same into gas of the desired pressure, and means for holding and releasing a torpedo.

5. A device of the class described including a torpedo tube having a breech, means for supplying a gas producing liquid to the 120 torpedo tube, means for heating the liquid for converting the same into gas of the desired pressure, and means for connecting the breech with a torpedo for holding the torpedo and for releasing the same, said means being adapted to cause the internal pressure to assist in holding the breech in position prior to the release of the torpedo. 130

6. A device of the class described including a torpedo tube having a breech, means for supplying a gas producing liquid to the torpedo tube, means for heating the liquid 5 for converting the same into gas of the desired pressure, and means for connecting the breech with a torpedo for holding the torpedo and for releasing the same, said means including a rotary shaft extending 10 through the breech and having an exterior operating device and provided with an interiorly engaging arm, and a coacting member carried by the torpedo for engaging with the arm and for permitting disengagement 15 of the same by a rotary movement of the shaft.

7. A device of the class described including a torpedo tube, a breech for the torpedo tube provided with an interiorly arranged 20 casing forming a chamber and composed of a perforated disk of the diameter of the interior of the torpedo tube, and means for spacing the disk from the breech and for securing the disk to the said breech, a receptacle arranged in the space between the 25 disk and the breech and adapted to receive

a gas forming liquid, electrically heated elements located at the receptacle for raising the temperature of the gas forming liquid to produce gas of the desired pressure, and 30 means for supplying a current to the said elements.

8. A device of the class described including a torpedo tube, a breech for the torpedo tube, an evaporating cup carried by the 35 breech and arranged interiorly of the torpedo tube and adapted to receive a gas forming liquid, a feed pipe extending through the breech and connected with the receptacle, electrically heated elements extending into 40 the receptacle for supplying the feed to convert the liquid into gas of the desired pressure, and means carried by the breech for supplying current to the electrically heated elements. 45

In testimony whereof I affix my signature in presence of two witnesses.
